ABSTRACT OF THE DISCLOSURE

Apparatus for working and in particular polishing articles in a vessel having a vertical axis about which it rotates while the vertical axis rotates about another vertical axis spaced from the axis of the vessel, the bottom of the vessel being at least partially inclined so that the articles in the vessel undergo an alternating motion which is both vertical and horizontal.

The present invention relates to improvements in article working, and in particular polishing, apparatuses having a vertical working vessel.

Apparatuses of this type are known which comprise a platform rotating about a first vertical axis on which the working vessel, in which the articles to be treated are disposed, is mounted for rotation about a second vertical axis which is eccentric relative to the first axis. A transmission system having a chain and sprocket wheels of appropriate transmission ratio connects a first fixed sprocket wheel centered on the first axis to a second sprocket wheel which is centered on the second axis and integral with the working vessel. The absolute movement of the latter therefore results from the composition of the two elementary movements, namely a rotation of the vessel about the first axis and a rotation of the vessel about itself, namely about the second axis.

The apparatuses of this type impart to the articles and other bodies placed in the working tank, such as polishing agents/or abrasives in powdered form or in pieces, a centrifugal force which intensifies the alternating stirring or agitating action inside the vessel due to the rotation, for the working, and in particular polishing, of the articles therein.

In all the known apparatuses of this type having a vertical working vessel, the bottom face of the vessel is horizontal so that the relative movement of each article or individual body in the vessel is also horizontal.

The object of the present invention is to improve this type of apparatus so that it can effect an alternating stirring in two directions, namely in horizontal and vertical directions.

The invention provides an apparatus for working, and in particular polishing articles, said apparatus comprising a platform rotatable about a first vertical axis and at least one vertical working vessel mounted on said platform to rotate about a second vertical axis spaced from the first axis, a transmission system connecting a first fixed toothed wheel centered on the first axis and a second movable toothed wheel centered on the second axis and integral with the vessel so as to impart a movement of rotation of the vessel about the second axis when the platform rotates about the first axis, the bottom of the vessel being at least partially inclined relative to the horizontal, so as to produce an alternating movement of the articles and bodies placed in the working vessel, which is both vertical and horizontal.

The advantage of the apparatus according to the in-

2

vention is that it produces a more complete stirring or agitation of the bodies in the working vessel.

Moreover, the emptying of the liquid in the vessel can be effected very easily while operating by means of a pipe extending from the lowermost point of the bottom of the vessel.

The apparatus according to the invention has the additional advantage over similar apparatuses which have a horizontal axis of rotation and vessels having a lateral opening. Thus, owing to the fact that the vessel is closed at the upper part thereof by an easily removable lid, the filling thereof is very easy, as opposed to vessels having a lateral opening which result in a limitation of the dimensions of the articles introduced, in particular when it concerns assemblies provided with parts.

The vertical vessel can have any desired cross-section, this section being, however, preferably hexagonal or octagonal.

Further features and advantages of the invention will be apparent from the ensuing description with reference to the accompanying single drawing which is a vertical sectional view.

The apparatus according to the invention comprises a fixed stand 1 through which extends a vertical column 2 carrying a fixed toothed wheel 3 at the upper end thereof. The vertical axis $x-y$ of the column 2 constitutes the axis of rotation of a horizontal plate 4 which bears on rollers 5 having horizontal spindles carried by the stand 1 and evenly spaced apart about the axis $x-y$.

The plate 4 is extended downwardly by a sleeve 6 at the lower end of which is secured an annular runway 7, having a slightly frustoconical face on which rollers 8 roll. The rollers 8 are mounted on the stand 1 to rotate about axes which are slightly inclined relative to the vertical. The runway 7 is integral with a toothed wheel 9 which is driven in rotation by a suitable motor (not shown) through a chain or a gear train.

Mounted on the platform 4 is a work vessel 11 having a vertical axis x_1-y_1 which is spaced from the axis of rotation $x-y$ of the platform 4. This vessel can have any horizontal cross-sectional shape and in particular an octagonal shape, as illustrated. The vessel 11 has in the lower part thereof an inner skirt portion 12 having a generally frustoconical shape in which rollers 13 are mounted to rotate about horizontal axes, these rollers rolling along the upper face of the platform 4. The rollers 13 are evenly spaced apart around the axis x_1-y_1 of the vessel 11. Rollable along the outer face of the skirt 12 are rollers 14 having axes of rotation which are inclined relative to the vertical and are evenly spaced apart around the axis x_1-y_1 and mounted on supports 15 fixed to the platform 4. An outer cylindrical skirt 16, integral with the vessel 11, covers all the support rollers 14.

The vessel 11 is integral with a toothed wheel 17 which is fixed to its chassis and centered on the axis x_1-y_1 of the vessel. This toothed wheel 17 is coupled to the fixed toothed wheel 5 by a transmission system 18 (of the chain or gear type).

The vessel 11 comprises a vertical lateral wall 19 having a prismatic octagonal cross-sectional shape and is closed in the lower part thereof by a bottom wall 21, the upper face of which is inclined to the horizontal in accordance with the invention. A coating or layer 22 of plastics material, rubber or any other material which sufficiently resists to erosion, is advantageously adherized to the inner faces of the lateral wall 19 and the bottom wall 21.

When the apparatus is in operation, the vessel 11 is closed by an upper lid (not shown). The vessel also has an emptying aperture 23 which opens onto an outer spout 24 and is closed by a door 25.

When the apparatus is operating, that is, with the vessel 11 closed by the upper lid and filled for a polishing operation with articles to be polished and a powdered abrasive material, the wheel 9 is driven in rotation at a suitable speed by the motor (not shown). The rotary platform 4 thus rotates about the axis x-y, it being supported by rollers 5 and maintained in position by rollers 8. The vertical axis x₁-y₁ of the vessel therefore rotates about the axis x-y and at the same time rotates about the axis x₁-y₁ owing to the connection, afforded by the transmission system 18, between the fixed toothed wheel 3 and the movable toothed wheel 17.

The transmission ratio is chosen to suit the treatment it is desired to carry out.

It will therefore be understood that the materials contained in the vessel 11 are subjected to a relative stirring or agitating movement which alternates both in the horizontal plane and, owing to the inclined face of the bottom wall 21, in the vertical plane. In this way, a marked increase in this relative stirring movement and a higher rate of working is achieved.

According to another feature of the invention, a passageway 26 is provided for discharging or draining the liquid usually placed in the vessel, while the apparatus is operating. This passageway 26 has an upper aperture 27 located at the lower point of the inclined bottom wall 12 whereas at the lower end thereof it communicates with a vertical tube 28 which extends through, and is coaxial with, the toothed wheel 17. The tube 28 extends through an opening 29 in the rotary plate 4 and opens into a fixed cylindrical collector 31 carried by the column 2. This collector 31 has a centre aperture 32 for discharging the liquid received when draining.

In the course of the rotation of the vessel 11 about itself, the passageway 26 and the tube 28 rotate, at the same time as the toothed wheel 17, about the axis x₁-y₁.

The apparatus just described allows a very easy rinsing while in operation. In this case, it suffices to provide a water inlet connection in the centre of the upper lid and connect this inlet connection to a water supply by way of a flexible pipe.

Although a specific embodiment of the invention has been described, many modifications and changes may be made therein without departing from the scope of the invention as defined in the appended claims.

Thus, in order to balance the apparatus, a plurality of vessels can be rotatably mounted on the platform 4 in even manner about the axis x-y.

The bottom wall 21 of the vessel is not necessarily plane. Depending on the desired applications, it can be given any suitable shape; for example it can be corrugated or conical.

The vessel 11 can be mounted on the platform 4 and the latter on the fixed stand 1 by means of intermediate oiling elements (for example balls, rollers, needles or truncated cones) for example of synthetic material, rubber or metal capable of supporting the weight of the moving parts and withstanding the lateral reactions during the movement of the latter. These moving parts could be advantageously freely mounted, that is, without embodied axes, between two runways or races with, if necessary, a cage for maintaining the spacing therebetween.

Having now described my invention what I claim as new and desire to secure by Letters Patent is:

1. An apparatus for working, and in particular polishing articles, said apparatus comprising a platform rotatable about a first vertical axis and a working vessel mounted on said platform to rotate about a second vertical axis spaced from the first axis, a transmission

system connecting a first fixed toothed wheel centered on the first axis and a second movable toothed wheel centered on the second axis and integral with the vessel so as to impart a movement of rotation of the vessel about the second axis when the platform rotates about the first axis, the vessel having a substantially vertical lateral wall and a bottom inner face which is at least partially inclined relative to the horizontal, so as to produce an alternating movement of the material in the working vessel, which is both vertical and horizontal.

10 2. An apparatus as claimed in claim 1, comprising a passageway for draining the vessel, said passageway communicating at one end with the lowermost point of the bottom face of the vessel and at the other end with a vertical discharge tube which extends through said movable toothed wheel and into a cylindrical collector located under the rotary platform and has an axis coinciding with the axis of rotation of the platform.

15 3. An apparatus as claimed in claim 1, wherein said lateral wall of the vessel is provided with an aperture at the lower point of said bottom wall, a door being provided for closing said aperture when the apparatus is in use and for opening said aperture and discharge the material from the vessel when the polishing step is over.

20 4. An apparatus as claimed in claim 1, wherein said toothed wheels are identical whereby the rotation speeds about said axes are equal.

25 5. An apparatus for polishing articles, said apparatus comprising a platform rotatable about a first vertical axis and a working vessel mounted on said platform to rotate about a second vertical axis spaced from the first axis, said toothed wheels being identical so that the rotation speeds about said axes are equal, the vessel having a substantially vertical lateral wall, a detachable cover and a transmission system connecting a first fixed toothed wheel centered on the first axis and a second movable toothed wheel centered on the second axis and integral with the vessel so as to impart a movement of rotation of the vessel about the second axis when the platform rotates about the first axis, the vessel having a substantially vertical lateral wall and a bottom inner face which is at least partially inclined relative to the horizontal, so as to produce an alternating movement of the material in the working vessel, which is both vertical and horizontal, said lateral wall of the vessel being provided with an aperture at the lower point of said bottom wall, a door being provided for closing said aperture when the apparatus is in use and for opening said aperture and discharge the material from the vessel when the polishing step is over, and a passageway being provided for draining the vessel, said passageway communicating at one end with the lowermost point of the bottom face of the vessel and at the other end with a vertical discharge tube which extends through said movable toothed wheel and into a cylindrical collector located under the rotary platform and has an axis coinciding with the axis of rotation of the platform.
